(57) **CLAIM**

The ornamental design for a pet carrier, as shown and described.

DESCRIPTION

FIG. 1 is a perspective view of the pet carrier.

FIG. 2 is a bottom view of the pet carrier.

FIG. 3 is an end view of the pet carrier. The cross-hatching denotes fabric.

FIG. 4 is side view of the pet carrier; and,

FIG. 5 is a top view of the pet carrier.

The broken lines depict portions of the pet carrier that form no part of the claimed design.

The pet carrier of the present invention is characterized by ornamental features resulting in the design and style of the invention.
